UNITED STATES PATENT OFFICE.

CHARLES E. WARD, OF NEW YORK, N. Y.

NECKSCARF.

SPECIFICATION forming part of Letters Patent No. 288,387, dated November 13, 1883.

Application filed May 3, 1883. (No model.)

To all whom it may concern:

Be it known that I, CHARLES E. WARD, of the city and county of New York, in the State of New York, have invented certain new and 5 useful Improvements in Made Scarfs for the Neck, of which the following is a specification.

My invention relates to that class of made scarfs which have a front piece and neckband; 10 and my improvement consists in a novel construction of said band, whereby it will be prevented from rising or riding up over the collar, and will tend to bring the scarf, with its front, to a central position and prevent it 15 from moving around the neck.

In the accompanying drawings, Figure 1 represents a scarf made according to my invention, with end of the neckband fastened in the position it will be in when upon the neck. Fig. 2 represents the same scarf with 20 the neckband unfastened.

Similar letters represent like parts in both figures.

The scarf represented has its front composed 25 of the center piece or shield, A, and the two side flaps, B and C; but the front may be otherwise constructed in any well-known or suitable form.

D E F is the neckband, having its ends E F 30 wider than the center or intermediate portion, D. One end, E, of the band is secured permanently to the front of the scarf, by sewing or otherwise, in such manner that its connection is not visible from the outside, and the other 35 end, F, is free, and is provided with an adjustable fastener or stiffener, similar to those of other made scarfs, to allow the said end F to be attached to the scarf back of the side flap, C.

40 *g* and *h* are shoulders formed by the increased width of the ends of the band, and on the lower edges of the same.

When the scarf is fastened on the neck in 45 the position shown in Fig. 1, the narrowness of the central portion, D, of the band will prevent said band from rising or riding up over the collar, and the shoulders *g* and *h*, coming in contact with the shirt-front, and in some cases with the vest of the wearer, will tend to

make the scarf self-adjusting to bring its front 50 to a central position, and also prevent it from turning around out of place. This form of the band, with the narrow portion D and shoulders *g* *h* on the lower edge of the band, obviates the necessity of pinning the band to the shirt or 55 collar, either for the purpose of preventing the band from working up or for keeping the front central.

When a pin is used for keeping the band in 60 place, unless great care is taken to get the scarf, with the front, in a central position, the pin through it may secure it out of proper position. By my invention the scarf automatically attains and preserves its desired central position.

65 The narrow portion D of the neckband may have its central part composed of or be entirely composed of elastic material, as shown at *i*, in order to make the scarf set closer upon the neck and to secure the tightening of the 70 same. This elastic material may be in the form of a narrow web or a cord.

Having now described my invention, what I 75 claim as new, and desire to secure by Letters Patent, is—

1. A made scarf for the neck, composed of a front and a band, which is attached permanently to one side of the said front, and provided with an adjustable attachment to the other side thereof, the portion of the band which surrounds the neck being narrower than the portions which are attached to the front, and the band having shoulders *g* *h* in its lower edge at the junction of its narrow and wider portions, whereby the scarf will be properly 85 centered and held in a central position, substantially as herein described.

2. A made scarf for the neck, composed of a front and a band, which is attached permanently to one side of the said front, and provided with an adjustable attachment to the other side thereof, the middle part of said band being elastic and narrower than the attached parts, substantially as herein described.

CHAS. E. WARD.
